US00D816055S

(12) **United States Design Patent** (10) **Patent No.:** **US D816,055 S**
(45) **Date of Patent:** **** Apr. 24, 2018**

(54) **MOBILE PHONE**

- (71) Applicant: **Samsung Electronics Co., Ltd.**, Suwon-si (KR)
- (72) Inventors: **Sanghoon Song**, Gumi-si (KR); **Youn-Gun Jung**, Suwon-si (KR); **Yoonyoung Choi**, Seoul (KR); **Junyoung Lee**, Seoul (KR)
- (73) Assignee: **SAMSUNG ELECTRONICS CO., LTD.**, Suwon-si (KR)
- (**) Term: **15 Years**
- (21) Appl. No.: **29/598,693**
- (22) Filed: **Mar. 28, 2017**

(30) **Foreign Application Priority Data**

- Nov. 11, 2016 (KR) 30-2016-0054405

(57) **CLAIM**

The ornamental design for a mobile phone, as shown and described.

DESCRIPTION

FIG. 1 is a front perspective view of a mobile phone showing our new design according to a first embodiment; FIG. 2 is a front elevation view thereof; FIG. 3 is a rear elevation view thereof; FIG. 4 is a left side elevation view thereof; FIG. 5 is a right side elevation view thereof; FIG. 6 is a top plan view thereof; FIG. 7 is a bottom plan view thereof; FIG. 8 is a rear perspective view thereof; FIG. 9 is a front perspective view of a mobile phone showing our new design according to a second embodiment; FIG. 10 is a front elevation view thereof; FIG. 11 is a rear elevation view thereof; FIG. 12 is a left side elevation view thereof; FIG. 13 is a right side elevation view thereof; FIG. 14 is a top plan view thereof; FIG. 15 is a bottom plan view thereof; and, FIG. 16 is a rear perspective view thereof.

The dashed broken lines in the drawings depict portions of the mobile phone that form no part of embodiment in which they are shown.

1 Claim, 14 Drawing Sheets
